UNITED STATES PATENT OFFICE

109,224

DESIGN FOR A FRUIT BOX

Fred R. Leuschen, Highland, Calif., assignor to Cherokee Citrus Co. Inc., Highland, Calif.

Application January 22, 1938, Serial No. 74,475

Term of patent 7 years

To all whom it may concern:

Be it known that I, Fred R. Leuschen, a citizen of the United States, residing at Highland, in the county of San Bernardino and State of California, have invented a new, original, and ornamental Design for Fruit Boxes, of which the following is a specification, reference being had to the accompanying drawing, forming part thereof.

The sides of the box opposite to those shown are substantially the same as the sides illustrated.

I claim:

The ornamental design for a fruit box, as shown.

FRED R. LEUSCHEN.
